SALES CHECK SYSTEM

Filed Jan. 5, 1922

Inventor:

Charles T. Raschick

Br. ~~Amalgamated~~
his Attorney.

UNITED STATES PATENT OFFICE.

CHARLES T. RASCHICK, OF ST. PAUL, MINNESOTA.

SALES-CHECK SYSTEM.

Application filed January 5, 1922. Serial No. 527,183.

My invention relates to sales check systems and has for its object to provide a sales check having groups of figures thereon with means for severing and punching said check 5 selectively any of the said figures in any of said groups.

Another object is to provide a check having several groups of figures, which figures are arranged progressively along the check 10 with means for severing the said check jointly along a line exposing at the edge of said check a figure from all of said groups with additional means for punching one of said checks at the line of severance thereof 15 so as to selectively designate any figure contained upon the whole check.

Another object of the invention is to form a sales check having numerals thereon arranged progressively in columns with means 20 for severing said check across all of said columns between any of the numerals thereof and in addition a movable cutter adapted to be positioned adjacent any of the exposed figures so as to simultaneously notch any 25 desired figure along the edge of severance of the check whereby any figure upon the check may be designated for payment.

In carrying out my objects I provide a cutter adapted to slide longitudinally relative to the columnar arrangement of the numerals on the check, which cutter is adapted to cut the check across all of the columns along a straight line. Upon said cutter I provide a slidably mounted auxiliary notching device which as the check is removed is 30 adapted to notch the portion of the check adjacent the cutting edge of said cutter, which notching device may be moved relative to the said cutter so as to notch the exposed figure in any of the columns on the 35 check.

The full objects and advantages of my invention will appear in connection with the detailed description thereof, and are particularly pointed out in the claims.

In the drawings, illustrating the application of my invention in one form:—

Fig. 1 is a front elevational view of my improved invention.

Fig. 2 is a side elevational view of the structure shown in Figure 1.

Fig. 3 is a view of a check after the same has been detached from the check pad.

Fig. 4 is a view similar to Figure 3 of another detached check designating a different amount for payment.

In the drawings I have shown a check holder indicated in its entirety at A, which comprises a body member B and a slidable member C mounted thereon. Body member 60 B is formed with a plate or back 10 which is of a rectangular shape and which is formed at one end with an upwardly turned lip 11 and which is formed near its other end with an upwardly turned stop 12 pressed 65 out of the body of the material forming the said back. Between the lip 11 and the stop 12 is positioned a check pad 13 having the leaves thereof stitched together as indicated at 14. A pointed extension 15 is formed on 70 the extreme end of the lug 12, for holding the pad 13 on the holder.

The back 10 is preferably formed of a uniform width throughout its length and has mounted upon it the slidable carrier 75 C which comprises a back 16 having a pair of upwardly turned members 17 and 18 positioned on each side of the same on one end thereof, and a pair of downwardly turned members 19 and 20 positioned on each side 80 thereof on the opposite end. The members 17 and 18 serve to guide the carrier C along the bottom of the back 10 and also serve to attach the cutter supporting member to the said carrier. At the extreme ends of 85 the members 17 and 18 the same are formed with clamping heads 21 which are adapted to hold rigidly the two ends 22 of a spring supporting member indicated at its entirety at D. This member has a transverse portion indicated at 24 on which is supported the cutter of my invention, which transverse portion has two arms 25 and 26 issuing therefrom at right angles, said arms being coiled at 27 and 28 with two convolutions 90 which extend towards the other end of the device to form two other bent arms 29 and 30. These arms as best shown in Figure 2 terminate in the portions 22 by means of 95 which the said spring supporting member D is attached to the carrier C.

For holding the coiled portions 27 and 28 of the spring supporting member D in proper position the previously mentioned downwardly turned members 19 and 20 are 100 passed through the said coiled portions and bent towards one another to prevent the said spring member from disengagement from the device, and to hold the said spring member in position along the sides of the back 10 as the device is moved along the same.

The cutter proper consists of a member

31 which is of rectangular shape and extends across the face of the check pad 13. This member is formed with a cutting edge 51 extending across one edge of the same 5 and with two upstanding ears 32 and 33 through which the transverse portion 24 of the spring supporting member D passes, and on which the said cutter is pivotally mounted. It can readily be comprehended 10 with the construction of the spring member D that this cutter is adapted to be held snugly against the uppermost check or the pad of checks 13 regardless of the number of checks remaining in the said pad or the 15 height of the same, and that the said carrier C may be readily slid along the cutter and pad so as to position the cutter 31 wherever it is desired.

For holding the stubs of the checks out 20 of the way after the checks proper have been severed from the pad I provide an arched clip 34 formed with two outwardly extending ears 35. These ears are adapted to be positioned between two similar ears 25 36 turned up from the body of the back 10. A single rivet 37 passing through all four of said ears pivotally holds the clip 34 mounted on the back 10. By raising the forward end of clip 34 which is formed 30 with a curved foot at 38 the check stubs may be conveniently inserted beneath the said clip as the said stubs are severed from the check proper. For forcing the foot 38 down upon the said stubs I provide a coil 35 spring 40 which is positioned about the rivet 37 as shown in dotted lines in Figure 1, and which has one end 41 hooked about one of the ears 36 and the other end 42 hooked to the rearward portion of clip 34. With 40 this means suitable pressure is brought to bear upon the folded over portions of the stubs indicated at 43 so that the same are conveniently held out of the way permitting the carrier C to be slid along and the holder 45 31 to be positioned wherever desired on the face of the check.

With my improved invention I prefer to use a check having a number of numerals on the same which are arranged in two or 50 more columns. In the form of the device illustrated I have indicated numerals in five columns 101, 102, 103, 104, and 105, those in column 101 commencing with zero and ranging by fives up to ninety-five and those 55 in each succeeding column starting with the numeral greater than the corresponding numeral of the preceding column by one and also ranging by fives up to an amount greater by one than the highest amount 60 nearest adjacent the preceding column. In this manner the combined numerals indicated on the check range by ones from zero to ninety-nine inclusive. At the head of the column the words "Pay highest amount 65 punched" are printed as indicated at 46 and

immediately above this a serial number shown at 47 and waiter number shown at 48 may be provided. A similar serial number 49 and waiter number 50 are positioned on the stub end of the check at the lower 70 portion of the same.

In using the device a check is severed along a line across all of the columns of figures by means of cutting edge 51 which leaves the figure desired at the lowermost 75 margin of the severed check, together with a figure of each of the other columns. For designating the particular figure of all of the columns exposed I provide a sliding runner 110 which is formed with a body 80 portion 111 having a pointed cutter 112 issuing outwardly from the edge thereof, which cutter is positioned beyond the cutting edge 51 of the member 31. Issuing upwardly from body member 111 are provided 85 two ears 113 which are each formed with notches 114 into which the transverse portion 24 of spring member D is adapted to pass. By this means the runner 110 is held slidably mounted upon said wire member 90 24 so that the said pointed cutter 112 can be slid to come in line with any of the columns 101 to 105 inclusive. When the check is torn off the pointed cutter 112 is positioned opposite the column required and 95 it can be clearly seen that as the check is severed a portion of the edge of the same is notched out. When cutter 112 is positioned as shown in Figure 1 a check such as shown in Figure 3 is produced. In this manner a 100 check may be issued for any amount ranging from one cent up to ninety-nine cents inclusive by properly positioning the cutter 112 and severing the check on the required line.

For issuing a check greater than one dollar I provide numerals zero, one, two, three, four and five at the extreme upper margin of the check as indicated at 115, which numerals are separated by perforated lines 117 and 118 so that the portion 110 of the check bearing these numerals can be readily removed from the remainder of the check. When the first portion having the numerals zero thereon is removed it would 115 indicate that the check was for one dollar and a number of cents equal to the highest punch mark in the lower margin of the check. In Figure 4 such a check is shown which is made out for \$1.73. If desired 120 instead of using perforated lines for removing portions of the check having dollar marks thereon the same may be omitted and the edges of the check marked by means of cutter 112 by tilting the said cutter back- 125 wards and inserting the upper end of the check beneath the same after which the said check may be notched by tearing the check against the said cutter. In using the device in this manner figure zero is omitted. 130

No punch mark along the upper edge indicates that the sales are less than one dollar. When the sales come to an even dollar the dollar mark at the upper edge is indicated

5 and the check severed below the lower row of figures with the punch mark at zero.

In accordance with the patent statutes 1 have described the principles of operation of my invention together with the apparatus 10 which I now consider to represent the best embodiment thereof, but I desire to have it understood that the construction shown is only illustrative and that the invention can be carried out by other means and applied 15 to uses other than those above set forth within the scope of the following claims.

I claim:—

1. A check severing device comprising an elongated support adapted to extend longitudinally of the checks, a plate like member 20 slidably mounted upon the rear of the said support, said plate like member having ears formed at the corners thereof extending upwardly along the edges of said support, a 25 spring member secured to the ears of said plate like member and having a portion positioned transversely across said support, a cutter hingedly connected to said trans-

verse portion and a notching device slidably mounted upon said transverse portion having a cutting edge extending outwardly beyond said cutter. 30

2. A check severing device comprising an elongated support adapted to extend longitudinally of the checks, a cutter extending 35 transversely of the support, means for slidably mounting said cutter upon said support, a notching device and means for supporting said notching device for movement at right angles to the movement of said 40 cutter.

3. A check severing device comprising an elongated support adapted to extend longitudinally of the checks, a cutter extending transversely of the support, means for slidably mounting said cutter upon said support, a pair of upturned ears formed in said cutter, a wire member extending through said ears, an auxiliary cutter having a pair of upturned ears, said latter ears having 50 notches therein adapted to engage said wire member for slidably holding said auxiliary cutter upon said transverse cutter. 45

In testimony whereof I affix my signature.

CHARLES T. RASCHICK.
